TAILPIPE OR AFTERBURNING CONTROL FOR TURBOJET ENGINES

Frank C. Mock and Thomas J. Thompson, South Bend, Ind., assignors to Bendix Aviation Corporation, South Bend, Ind., a corporation of Delaware

Application April 22, 1949, Serial No. 89,054

35 Claims. (Cl. 60—35.6)

This invention relates to turbojet engines for aircraft, 15 and is particularly concerned with means for obtaining thrust augmentation in such engines by burning fuel in the tailpipe or tail cone section thereof.

The instant application incorporates, but does not claim, certain subject matter common to the following copending U. S. applications (common assignee): Serial No. 25,828, Mock, filed May 8, 1948, now Patent No. 2,736,166, issued February 28, 1956; Serial No. 30,828, Thompson, filed June 3, 1948; Serial No. 82,792, Kuzmitz, filed March 22, 1949.

This method of obtaining thrust augmentation is commonly termed "tailpipe burning" or "afterburning." In the following description, the latter term will be more frequently used for the simple reason that it is the shorter of the two, although perhaps less apt.

When burning fuel in the tailpipe area after the turbine, it is important to maintain a balanced condition between the turbine and compressor, and this in turn calls for coordinated regulation of the rate of fuel feed and exhaust jet nozzle area. In Serial No. 25,828, the two principal factors to be controlled, viz. jet nozzle area and the rate of fuel feed, are coordinated by interconnecting the gate valves which control the exhaust jet nozzle and the afterburning fuel metering means through a suitable corrective device which responds to a preselected ratio of tailpipe and ram or compressor inlet pressure in one instance and temperature in the other. In Serial No. 30,828, the means for maintaining a prescheduled rate of fuel feed and jet nozzle area includes a device which operates as a function of engine speed. In Serial No. 82,792, the rate of supply of the afterburning fuel is a function of compressor discharge pressure and jet nozzle area. In the latter application, also, when the pilot sets his control lever for afterburning, such will not take place unless the aircraft is traveling below a predetermined rate of speed, nor can the gate valves open and full afterburning be had until a certain amount of starting fuel has been burned in the tailpipe chamber.

In the present application, compressor discharge (P_c) pressure is also used as a metering modulus, and here again jet nozzle area and the rate of fuel feed is coordinated, but coordination is had across the throttle valve and interrelated regulator system of an afterburning fuel metering device and is subject to modification by means responsive to tailpipe temperature. When the pilot sets his control for afterburning, the latter will not occur unless or until a certain predetermined engine speed is attained, whereupon starting fuel is first supplied to the tailpipe chamber and ignited, and when the temperature in said chamber rises to a certain value, the area of the exhaust jet is increased and simultaneously therewith afterburning fuel is metered to all of the afterburning nozzles and ignited for normal or full afterburning operation, during which the rate of fuel feed is governed as a function of P_c pressure subject to correction by means operating as a function of tailpipe temperature to maintain the latter constant.

2

An object of the present invention, therefore, is to simplify and generally improve afterburning systems for turbojet engines.

A more specific object is to provide improvements in the means for coordinating the fuel metering rate and exhaust jet nozzle area to obtain maximum overall engine efficiency.

Another object is to provide metering means for the afterburning fuel which operates automatically as a function of compressor discharge pressure and/or temperature and which is subject to correction by means responsive to tailpipe temperature to maintain the latter at some predetermined value.

A further object is to provide automatically operating afterburning devices responsive to engine speed and tailpipe temperature to insure against overspeeding of the engine should the starting fuel fail to burn or in case of lack of afterburning fuel or failure of the fuel supply.

Other objects and advantages will become apparent in view of the following description taken in conjunction with the drawings, wherein:

Figure 1 is a schematic view of a turbojet engine equipped with an afterburning system in accordance with the present invention;

Figure 1A is an enlargement of the upper left-hand portion of Figure 1 to more clearly show the structure thereof;

Figure 2 is a sectional schematic of the afterburning fuel control device of Figure 1;

Figure 3 is an electrical diagram of a type of temperature correcting and amplifier unit which may be used for modifying the rate of fuel feed to obtain a constant or predetermined tailpipe temperature; and

Figure 4 is a schematic sectional view of a modification in the afterburning fuel control device of Figures 1 and 2.

The turbojet engine shown more or less diagrammatically in Figure 1 and generally indicated at 10 includes a burner system made up of a plurality of annularly-arranged combustion chambers 11, each having therein a flame tube 12, the walls of which are formed with a series of openings 13 for admitting air thereto from its surrounding chamber 11. An air adapter or header section 14 is detachably connected to the front end of the burner assembly and directs air under pressure to the chambers 11, where part of the air enters the flame tubes 12 through the holes 13 and mixes with the fuel discharged from burner nozzles 15, there being one for each flame tube. The gases comprised of expanded air and products of combustion are discharged from the flame tubes through stator blades 16 and turbine blades 17, the latter forming part of a turbine rotor 17. A dynamic compressor is generally indicated at 18; it is shown as being of the centrifugal type, but may, of course, be of the axial flow type; it is driven from the turbine and is shown mounted on a shaft 19 common to the turbine rotor and compressor.

Beyond the turbine is the tailpipe 20; it carries a diffuser cone 21 at its entrance end and at its outlet terminates in a reaction jet or nozzle 22, the area of which is adjustable by means of a pair of gate valves 23 and 24 mounted on suitable bearings such as trunnions or short shafts 25 and 26. Also secured on said shafts are intermeshing segmental gears 27 and 28. An arm 29 is secured at one end on the shaft 25 and at its opposite end is connected through the medium of a link rod 30 with a servo piston 31 slidably mounted in a cylinder 32. The piston 31 is preferably operated by compressor discharge or P_c pressure in a manner to be described.

Any suitable type of main fuel supply system may be adopted, that shown in the present instance and generally designated at 33 in Figures 1 and 1A is of the type illustrated in a copending application of Frank C. Mock,

Serial No. 716,154, filed December 13, 1946, now patent No. 2,689,606, issued September 21, 1954, and assigned to the assignee of the present application. Fuel is supplied under pressure from a suitable source of supply such as a fuel tank, not shown, by way of conduits 34, 34' in which is mounted an engine-driven fuel pump 35 of the positive displacement type having a by-pass 36 controlled by a suitable by-pass valve, not shown, but which is adapted to maintain the supply pressure at a predetermined value over and above metered fuel or discharge pressure. The device indicated at 37 is a bellows housing which forms part of a density control system for regulating the rate of fuel feed to the burners 12 as a function of changes in pressure and temperature of the air flowing to the engine. The metered fuel from the main fuel control 33 flows by way of a conduit 38 to a fuel manifold 39, from which it flows to the respective burner nozzles 15 through a series of branch nozzle pipes 40.

An emergency fuel metering system is usually provided. In the present instance it is shown in block diagram at 41 and may be in the form of an engine driven fuel pump located in an extension 42 of the conduit 34', the fuel being by-passed around the main fuel control 33 by way of a conduit 43 and thence through a double check valve 44 into the conduit 38. The emergency system is primarily for use in case the main fuel control should fail or become ineffective and may be controlled by the pilot in any suitable manner, not shown.

The rate of fuel feed is under selective control from the pilot's compartment by means of a suitable power lever 45 adjustable along a quadrant 46, said lever being pivoted at 47 and connected by suitable linkage 48 to the governor or throttle valve of the main fuel control. Purely by way of example, the quadrant has indicated thereon four control positions, viz. "fuel cut-off," at which position all fuel flow to the burners is stopped and the engine is closed down; "idle," at which position the engine is operating at a suitable idling speed; "maximum power," at which setting the engine is delivering at some predetermined maximum power output on the main fuel control; and "augmented power," at which position the after burning system is placed in condition for operation automatically in a manner to be described.

The lever 45 is provided with a lateral projection 50 movable in a slot 51 formed in the quadrant 46; and when the said lever is set at "augmented power," the projection 50 moves into a communicating offset slot 52 and depresses a switch plunger 53, forming part of a main control switch, generally indicated at 54 and including a pair of contacts 55 and 56 adapted to be bridged by a conductor 57 when the plunger 53 is depressed. This energizes a circuit leading by way of wires 58, 59 and 60 from a suitable source of electric power, indicated as a battery 61, to a speed-sensitive switch, generally indicated at 62, adapted to respond to changes in engine speed. In the form shown, the switch 62 is responsive to the differential between unmetered fuel pressure in the regulator chamber of the main fuel control and unmetered fuel pressure in the governor chamber in the immediate area of the rotating governor weights and which pressures vary with variations in engine speed but are unaffected by changes in air density or altitude. A differential exists between these respective pressures (commonly termed P_2 and P_2' pressures) due to the fact that the governor chamber pressure is augmented or amplified by the centrifugal action of the rotating governor weights, one of which is visible in the said governor chamber. Said switch 62 has a pair of contacts 63 and 64 adapted to be bridged by a conductor 65, carried by a diaphragm 66, which constitutes a movable wall between chambers 67 and 67'. P_2 pressure is communicated to the chamber 67 by a conduit 68, and P_2' pressure is communicated to the chamber 67' by a conduit 68'. A light spring 69 normally urges the diaphragm toward a non-contacting position.

When the speed responsive switch 62 is closed, the solenoid coil 71 of a magnetic clutch 72 is energized by way of line wires 73 and 74. This action starts operation of a constant displacement engine-driven pump 75 which takes fuel from the main fuel line 34 by way of conduit 76 and pressurizes it by way of conduit 77 to the intake chamber 78 of an afterburning fuel control unit generally indicated at 79 and shown more or less in detail in Fig. 2. Should the fuel in the chamber 78 exceed a predetermined pressure, it opens a by-pass valve 81 and fuel may then pass back to the low pressure side of the pump 75 by way of port 81', chamber 82 and return conduit 83. The by-pass valve 81 is connected to a diaphragm 84, which forms a movable wall between the chamber 78 and a chamber 85 in which a spring 86 is mounted and normally urges the valve 81 towards seated position. The chamber 85 is preferably vented to metered fuel or discharge pressure by way of passage 87 having a suitable restriction 87" therein, and passage 87", so that the valve 81 (which is of the balanced type) will maintain the pressure in the chamber 78 at a predetermined value over and above metered fuel pressure as determined by the strength of the spring 86. A normally closed spring loaded relief 80 is mounted inside valve 81, and is adapted to open a port in the end wall of valve 81 for relieving the pressure in chamber 78 in the event it exceeds a predetermined maximum value.

A regulator valve is indicated at 88; it is of hollow cylindrical form and provided with ports 89 adapted to register with ports 90 formed in a similarly-shaped coacting valve 91 which is slidably telescoped into the valve 88. The valve 88 is controlled as a function of tail-pipe temperature in a manner to be described, while the coacting valve 91 is controlled as a function of jet nozzle area, also in a manner to be described. Fuel from chamber 78 flows into annular valve chamber 92 and thence across ports 89, 90 and 90' into chamber 93. From this chamber, fuel flows across a metering valve 94, which is provided with ports 95 and is mounted to slide in a cylindrical valve casing 96 provided with ports 97, the ports 95 and 97 coacting to provide a variable metering restriction. The valve 94 is connected to and actuated in response to movement of a capsule or bellows 98 provided with a connecting stem 99, said bellows being mounted in a chamber 100 to which compressor discharge or P_e pressure is communicated by way of conduits 101 and 102. A calibrated drain bleed 103 vents the chamber 100 to the atmosphere or other suitable low pressure source.

Reverting now to the regulator valve 91, it is connected to a diaphragm 104, which forms a movable wall between the chamber 93 and a chamber 105, vented to metered fuel or discharge pressure by way of a passage 106 having a calibrated bleed or restriction 107 therein. The chamber 105 is also preferably vented to the chamber 93 across diaphragm 104 by a passage 109 having a calibrated restriction 108' therein. A spring 109 engages the diaphragm 104; its effective force is adapted to be varied or adjusted by means of a cam 110 mounted on a shaft 111; and the tail gate servomotor piston 31 is operatively connected to the said cam shaft by means of a rod 112, bell crank lever arms 113, 113', link rod 114 and arm 115, the said bell crank being pivotally anchored at 116, compare Figs. 1 and 2.

The fuel metering rate across the regulator 79 will vary as a function of (a) P_e or compressor discharge pressure through variation of the metering restrictions or ports 95, 97 in response to movement of the bellows or capsule 98; (b) exhaust nozzle area through variation of the metering head by rotation of cam 110 in relation to movement of the tail gate valves 23 and 24 and consequent repositioning of valve 91, and (c) tailpipe temperature also through variation of the metering head by repositioning of valve 88 due to the action of the temperature responsive device of Fig. 3 to be described. At any given position of valves 94, 88 and 91, the regulator will be in balance and the

head across valve 94 will be constant; and if at such time the area of the metering restrictions 95, 97 be increased, there will be an increase in flow across said restrictions and also a momentary reduction in the differential across diaphragm 104, whereupon valve 91 will open to re-establish the differential and balance the regulator; a reduction in the area of the metering restrictions having the opposite effect. Likewise, if at any given position of valve 94 either one or both of the valves 88 and/or 91 be repositioned, there will be a variation in the metering head and a consequent increase or decrease in the rate of fuel flow. The vent passage 108 is provided primarily to assist in the removal of any vapors that may tend to form in the regulator and thereby unbalance the latter.

Fuel flowing across the valve 94 enters metered fuel chamber 117 and passes from this chamber through conduit 118, port 119 and conduit 120, first to the starting system, and after ignition and burning of the starting fuel, to the main afterburning fuel manifold and discharge nozzles.

Referring to the starting system, this may comprise one or more starting torches or nozzles, one of which is indicated at 121, receiving fuel from the conduit 120 by way of starting fuel manifold 122 and pipe 123. Starting fuel may also flow by way of pipe or conduit 124 to any selected one or more of the main fuel discharge nozzles, two of which are shown at 125, the latter receiving fuel from a main afterburning fuel manifold 126 and pipes 127. A spark plug or other suitable ignition device is indicated at 128; it is energized, when the speed responsive switch 62 is closed, by way of line wires 73, 74 and 129. To prevent flow of starting fuel into the manifold 126 and premature firing of the afterburning system, a check valve 130 is provided between the said manifold and any of the conduits 124 which supply fuel to the starting nozzle or nozzles. A starting cut-off valve is indicated at 131; it is of the normally closed electric type and has a solenoid coil 132 which is energized when the temperature in the tailpipe attains a certain predetermined value and opens the said valve to permit fuel to flow to all of the afterburning nozzles 125. Accordingly, a thermostatic switch, generally indicated at 133, is located in the tailpipe adjacent the exhaust jet nozzle 22; it includes a pair of contacts 134 and 135 carried by a pair of bimetallic elements 136, 136'. When speed responsive switch 62 is closed, current may flow by way of line wires 73 and 137 to the switch 133, and if the latter is also closed, then current will flow thereacross and by way of wire 137' to the coil 132 of the starting solenoid valve 131.

The tail gate control servo piston 31 is preferably actuated by compressor discharge pressure which is controlled by means of an electric servo comprising a valve 138 mounted to slide in a valve body 139. The valve 138 is normally urged toward closed position, or toward the left as shown, by a spring 140. The valve body 139 has an inlet port 141, a pair of outlet ports 142 and 143, and a pair of drain or air relief ports 144 and 145 opening to a common drainpipe or conduit 146. A solenoid coil 147 serves to actuate the valve 138 to the right, as shown, against the compressive resistance of the spring 140, the said coil being energized, when the switch 133 is closed, by way of line wires 137' and 148. A conduit 149 communicates port 142 with the servomotor cylinder 31 on the left-hand side of piston 31, and another conduit 150 communicates port 143 with said cylinder on the right-hand side of said piston.

In the position of the servo valve 138 as shown, P_e or compressor discharge pressure is being communicated to the left-hand side of piston 31 by way of conduit 101, ports 141, 142 and conduit 149, holding the said piston in a gate-valve-closing position. At this time, the temperature switch 133 is open and the solenoid coil 147 is de-energized. Under these conditions, the engine is operating on the normal fuel supplied by the main fuel control 33. Should temperature switch 133 close, coil 147

would become energized and servo valve 138 would move to the right and communicate port 141 with 143 and 142 with 144, whereupon P_e pressure would be communicated by way of conduit 150 to the servomotor cylinder 32 on the right hand side of piston 31 and the latter would move to the left, opening gate valves 23 and 24 to the position shown in dotted lines.

It will be noted that the P_e pressure line or conduit 102 to the bellows chamber 100 has a port 151 therein which is adapted to be opened and closed by a solenoid valve 152 controlled by a coil 153, the latter being electrically connected by wires 154 and 59 with contact 56 of the pilot's control switch 54. When the pilot sets his lever for afterburning, he automatically opens valve 152. This valve avoids leakage and consequent loss of pressure when the afterburning system is not being used.

The port 119 between the fuel conduits 118 and 120 is controlled by a valve 155, which is of the normally closed solenoid type and is opened through energization of coil 156, connected by line wires 157, 74 and 73 with the contact 64 of the speed sensitive switch 62. Thus, when switch 62 closes, valve 155 opens, and when switch 62 opens, valve 155 closes.

The means for repositioning the valve 88 of the fuel metering device 79 as a function of tailpipe temperature may be of any suitable type. In the example chosen for the purposes of illustration, it comprises an induction motor 160 having a control circuit shown in block diagram at 161 in Figure 1 and more in detail in the electrical diagram of Figure 3. The motor has a stator winding of the two-phase A. C. reversing type comprising a fixed phase field coil 162 and a variable phase coil 163. An alternating current potential may be had by means of a suitable inverter 164 having its input connected to a source of direct current potential, not shown, or the A. C. supply may be taken from a generator or other convenient source. The rotor 165 of the motor is connected to the valve 88 by means of an arm 166, link 167, arm 168, shaft 169, and slotted arm 170, the latter having a slot and pin connection with the stem of said valve (compare Figures 1 and 2). The means for sensing tailpipe temperature includes a thermocouple 171 which is electrically connected to a bridge circuit 172. The voltage impressed on the fixed phase coil or winding 162 is shifted nearly ninety electrical degrees with respect to the supply voltage by a series capacitor 173. The voltage impressed on the winding 162 is supplied through a saturable reactor 174; it is so designed that if tubes 175 and 176 are conducting the same average current, the voltage applied to the variable phase winding 163 will be zero and the motor will not run, but if one tube is conducting a plate current of greater magnitude than the other, a voltage will be applied to the winding 163 and the motor will run in one direction, the motor reversing when the current is of greater magnitude in the opposite tube.

The function of the bridge 172 and associated motor control circuit is to take a signal from the thermocouple 171 when the latter senses temperatures above and/or below a calibrated value and cause the motor arm 166 to make a partial turn in one of two opposite directions and position the valve 88 of the fuel control device 79 of Figure 1 in a manner such as to maintain the tailpipe temperature substantially constant. Also, when the afterburning system is turned off or is not being used, to cause the said valve to come to rest at a position corresponding to some predetermined tailpipe temperature, and which may be the calibration temperature at which the bridge 172 is balanced, so that when the afterburning system is again turned on, said valve will be already set at a position for establishing the desired temperature. Accordingly, the bias battery indicated at 177 is of such magnitude and direction as to cause tube shut-off when no current is flowing in the secondary 178' of transformer 179. However, when the A. C. grid voltage of either

tube 175 or 176 is in phase with the plate voltage between the points indicated at x , y , the tube will conduct. The phase-splitting transformer 179 supplies voltages to the grid circuits of tubes 175 and 176 which are 180 electrical degrees out of phase with one another. The primary 178 of transformer 179 is connected into the output circuit of an amplifier 181, which may be of the conventional audio type employing feed-back for stability purposes and is not shown in detail. The input circuit to the amplifier is connected across the secondary 182' of a transformer 183, the primary 182 of said transformer being connected across the signal circuit 184 of the bridge 172. The device indicated at 185 is a variable resistance or so-called "acustilator" comprising a container or box of carbon granules with a diaphragm 185' overlying the same which vibrates in response to changes in the magnetic field of coil 186; it functions to change the D. C. current flow from the bridge circuit to a pulsating current at a frequency determined by that of the power transformer 187. The direct current voltage impressed on the acustilator 185 and the primary 182 of transformer 183 is of a magnitude proportional to the degree of unbalance of the bridge 172 and of a polarity dependent on the direction of unbalance. In other words, the magnitude is proportional to the rise in tailpipe temperature above or the drop below a predetermined value, and the polarity changes each time the temperature goes above or below such value. Further, the periodic variations in resistance across the acustilator 185 produces a voltage output from the secondary 182' of transformer 183 of a magnitude proportional to the direct current voltage impressed on the acustilator and the primary 182 of said transformer, and a phase relationship with respect to the voltage between points x and y dependent upon the polarity of the applied direct current voltage.

A relay switch is indicated at 188; it is designed to connect the bridge circuit with the thermocouple 171 by engaging contact 189 when the afterburning system is in operation and to connect said circuit with the wiper arm 191 of a potentiometer 192 by engaging contact 190 when the said system is turned off. The switch 188 is held in engagement with contact 189 through energization of solenoid coil 193, which is electrically connected to contact 64 of the speed sensitive switch 62 of Figure 1 by means of wires 194, 157 and 73. The motor 160 has a follow-up connection with the wiper arm 191 by means of suitable mechanical linkage indicated at 196 in Figure 3.

The bridge circuit may be energized from a source of regulated direct current voltage shown in the form of a tube rectifier 197 having its input inductively coupled with the main supply through transformer 187 and its output connected through a voltage regulator tube 198 with the bridge input, the said tube 198 maintaining the voltage applied to the bridge circuit within close tolerances.

If at the time the afterburning system is turned off the motor should stop at some position at variance from the balanced setting of the bridge, the wiper arm 191 will be "off-center" and will unbalance the bridge in a direction such that the signal output of the transformer 183 will have a phase relationship to the motor winding 162 tending to rotate the motor in a direction to reduce the error, until the bridge output becomes zero at what may be termed a "false signal" having as its modulus some predetermined tailpipe temperature.

When the afterburning system is turned on and the speed sensitive switch 62 closes, relay coil 193 will be energized and move switch 188 into engagement with contact 189. This connects the thermocouple with the bridge circuit, and if at this time the temperature sensed by the thermocouple does not correspond to the calibration of the bridge, then the latter will become unbalanced in a direction such that the signal output of the trans-

former 179 will have a phase relationship to motor winding 162 such as to produce rotation of the motor in a direction to position valve 88 for correction by regulation of fuel flow.

Operation

Ordinarily, thrust augmentation by afterburning is not used until the maximum power available from the main burner system has been obtained by an advanced setting of the throttle or control lever 45. In the position of the control lever shown in Figure 1, the engine would be closed down and all flow of fuel to the burners cut off. Between cut-off position and up to and including the maximum power setting, the engine operates solely on the main burner system.

The various parts of the afterburning system are shown in a non-operating position, the master switch 54, which responds to the pilot's control lever 45, being open. Accordingly, the P_c solenoid valve 152 and the cut-off valve 20 155 are both closed; the speed sensitive switch 62 is de-energized as is also the safety starting temperature responsive switch 133; the switch 188 of the temperature responsive motor control unit of Figure 3 will be in a constant temperature "false signal" position (in engagement with contact 190); the magnetic clutch 72 of the fuel pump 75 will be released, and the spring 140 of the electric tail gate servo valve 138 will be holding the valve in the position shown, at which time the tail gates 23 and 24 are closed to a point where the area 30 of the jet nozzle 22 is such as will give maximum thrust under normal engine operating conditions.

Assuming the pilot is operating at a maximum power setting and decides to utilize the added thrust available by afterburning, he then moves the lever 45 to the augmented power position and simultaneously closes the switch 54, whereupon the P_c valve 152 is opened, and the speed sensitive switch 62 is energized. If we now assume that the speed of the engine is within a predetermined range tending toward maximum efficiency under 40 afterburning operating conditions, the speed sensitive switch 62 will close, whereupon (a) current will flow to the solenoid coil 156 of the cut-off valve 155 which controls the port 119 and opens said valve, (b) current will flow to the hot side of the temperature responsive safety starting switch 133; (c) the ignition system of 45 spark plug 128 will become active; (d) the switch 188 of the temperature responsive motor control unit of Figure 3 will be moved from its constant temperature false signal position to actual tailpipe temperature sensing 50 position (in engagement with contact 189), (e) the magnetic clutch 72 will close and start the pump 75 in operation so that it delivers fuel to the entrance chamber 78 of the fuel metering device 79, from which it flows across the regulator valves 88, 91 and metering valve 94 and 55 thence by way of conduit 118, port 119 and conduit 120 to the starting fuel manifold 122 and starting torch 121. The starting fuel flow now ignites and proceeds to burn in the tailpipe chamber and raise the temperature therein.

When the tailpipe temperature rises to a value such as 60 will cause the safety starting switch 133 to close, (f) the solenoid coil 147 of the electric servo valve 138 will be energized and the valve 138 will be moved to the right from the position shown and cause the servomotor piston 31 to move to the left and open the tail gate valves 23 and 24, and (g) the solenoid coil 132 of the normally closed fuel cut-off valve 131 will be energized and said valve will open, permitting fuel to flow to all 65 of the afterburning nozzles 125.

As the tail gate valves open, the cam 110 is rotated 70 in a counterclockwise direction, compressing spring 109 and opening the regulator valve 91 to increase the metering head across the valve 94. This provides a scheduled relationship between jet nozzle area and afterburning fuel flow, as required by the engine during the transition from normal to augmented thrust conditions.

The foregoing series of steps bring the afterburning system into full operation. It will be noted that the jet nozzle area will remain normal until after a sure indication is had that the tailpipe temperature had been increased by burning of the afterburning starting fuel. If at any time during the starting period there is a reduction in engine speed due for example to die-out in the normal burner system, the speed sensitive switch 62 will immediately open and prevent operation of the afterburning system. Furthermore, in case the afterburning system should fail, there would be a drop in temperature in the tailpipe chamber and switch 133 would open, shutting down the afterburning system and preventing loss of fuel and possible serious overspeeding of the engine.

During normal or full afterburning operation, the metering device 79 operates automatically to meter afterburning fuel as a function of compressor discharge pressure. The metering restrictions 95 are calibrated to provide as nearly as possible the correct scheduled fuel flow for efficient afterburning, any error being subject to correction by the action of the tailpipe temperature corrector. The corrective action of the P_c or compressor discharge responsive bellows or capsule 98 tends to increase the metering rate of the afterburning fuel as the engine speed increases, and to decrease such rate as the engine speed decreases, whereas the corrective action of the tailpipe temperature regulator tends to increase fuel flow as the tailpipe temperature drops and to decrease fuel flow as the tailpipe temperature rises. Thus, as the engine speed increases and P_c pressure rises, the bellows 98 is compressed and the area of the metering restrictions 94, 95 increases; and as the tailpipe temperature rises, the regulator valve 88 moves to the left and reduces the metering head across the valve 94, and as the temperature in the tailpipe drops, the said valve 88 moves to the right and increases the metering head across the said valve 94. By correlating the metering characteristics of the valve 94 with those of the valve 88, a stable operation of the afterburning system is obtained.

When the pilot moves his control lever out of the augmented power position, the master switch 54 opens, thereby cutting off current to the speed responsive switch 62 and the coil 153 of the P_c solenoid valve 152. Also, the controls which normally respond to the speed switch 62 are de-energized, viz. the magnetic clutch solenoid coil 71, the safety starting switch 133, and the relay coil 193 of the switch 183; whereupon the pump 72 idles, the electric servo valve moves back to the position shown, causing the gate valves 23 and 24 to close to normal thrust area, the temperature responsive motor control circuit is reset to constant temperature false afterburning signal, the fuel cut-off valves 119 and 131 close, shutting off all flow of fuel to the afterburning nozzles including the starting nozzles, and the spark plug 128 is de-energized.

Figure 4

In Figure 4, an afterburning fuel control system is shown which operates in a manner different from the fuel control of Figures 1 and 2 although the ultimate result is substantially the same. The fuel from the supply pump enters the unit under supply pump pressure by way of conduit 77', and flows across a regulator valve 200 which is slidably mounted in a ported sleeve or bushing 201, the sleeve and valve being provided with coating ports 202 through which the fuel flows to chamber 203. The valve 200 is connected to a diaphragm 204, which forms a movable wall between chambers 205 and 206, said diaphragm being backed by a spring 207 of substantially constant rate and which may be adjusted by means of screw 208.

The valve indicated at 209 is a throttle valve; it corresponds to the valve 94 of Figures 1 and 2. It is mounted to slide in a sleeve or bushing 210, said sleeve and valve

being provided with coating feed restrictions or ports 211. The fuel flowing across the valve 209 enters metered fuel chamber 212, from which it flows by way of conduit 118' to the afterburning starting and main fuel discharge nozzles 121 and 125 of Figure 1.

The valve 209 is operatively connected to the tail gate valves 23 and 24 of Figure 1 by means of a link rod 112', bell crank levers 213, 214 and valve stem or rod 215. Thus, as the tail gate valves open and close, a proportional movement will be imparted to the throttle valve 209, and at any given metering head across the throttle valve, fuel flow will be proportional to jet nozzle area. In the type of fuel control shown in Figure 4, instead of adjusting the throttle valve directly as a function of P_c or compressor discharge pressure, the metering head across the valve is varied as a function of compressor discharge pressure and a temperature varying as a function of engine or compressor inlet temperature subject to correction by deviation of turbine outlet or tailpipe temperature from a predetermined value. To accomplish this result, a fixed bleed 216 communicates chambers 205 and 206 across the diaphragm 204, and fuel in chamber 206 may by-pass the throttle valve 209 by way of passage 217, variable orifice 218, chamber 219, and passage 220. The variable orifice 218 is in series with the fixed bleed or orifice 216; it is controlled by a contoured needle 221, which at its outer end has a swivel or pivotal connection with a crank-shaped lever 222, secured on the lower end of a shaft 223, which projects upwardly through a sealed bearing in the housing of the unit into a chamber 224 and is adapted to be reversely rotated in response to movement of a bellows 225 and also by motor 160', which corresponds to the motor 160 of Figures 1 and 4 and is driven in reverse directions in response to signals from the temperature sensitive unit 161. Accordingly, the bellows 225 is provided with a rack gear 226 at its free or movable end which is constantly in mesh with a gear 227 formed on the lower end of a hub 227', the latter being mounted for free rotation on shaft 223 and at its opposite end having formed thereon another gear 228 constantly in mesh with one of a pair of planetary pinions 229 and 229', the latter being carried by a stub shaft 230' journaled in the peripheral portion of a drive plate 230, which is secured to and drives the shaft 223.

The motor 160' has a drive pinion 231 secured on the free end of its armature shaft which is in constant mesh with a gear 232, formed on the upper end of a hub 232', the latter like the hub 227' being mounted for free rotation on shaft 223. The lower or opposite end of the hub 232' has formed thereon a gear 233 in constant mesh with pinion 229'.

If gear 227 is rotated clockwise, for instance, gear 228 would also be rotated in the same direction and rotate pinions 229 and 229' in a counterclockwise or opposite direction. If at this time gear 233 is held against rotation, then the pinion 229' will walk around the latter gear counter-clockwise and produce like rotation of the drive plate 230. Conversely, if gear 233 is rotated clockwise, pinions 229, 229' will rotate counter-clockwise; and if at this time gear 227 is held against rotation, pinion 229 will walk around the gear 228 and produce like rotation of drive plate 230. Hence shaft 223 may be driven by movement of rack 226 or rotation of the motor drive gear 231, the drive of one being independent of the other. The differential mechanism shown in Figure 4 is simply for illustrative purposes only, it being understood that in practice any type of differential unit suitable for the purpose may be used.

The bellows 225 is mounted in a chamber 234, and regulated P_c or compressor discharge pressure is communicated to this chamber by way of conduit 235, chamber 236, variable orifice 237, chamber 238 and conduit 239. The orifice 237 is varied in relation to changes in compressor discharge temperature; its area is controlled

by a needle 240 secured to the free or movable end of a stack of by-metallic disks 241, which are located in chamber 236. These disks have the characteristic of contracting upon an increase in temperature and expanding upon a decrease in temperature. Thus an increase in compressor discharge temperature will move needle 240 in a direction to restrict orifice 237, a decrease in such temperature having the opposite effect. Obviously, the desired effect could be obtained by a temperature responsive unit working in the opposite direction with a reversely contoured needle. The wall of the bellows chamber 234 is provided with a bleed 237' in series with the variable orifice 237.

Assuming there is an increase in P_e or compressor discharge pressure at a given area of orifice 237 (constant temperature), the bellows 225 will collapse and produce rotation of the shaft 223 and crank arm 222 in a clockwise direction, thereby moving the needle 221 in a direction to restrict the orifice 218, an expansion movement of said bellows having a reverse effect. Should there be a change in compressor discharge temperature, the area of orifice 237 will be correspondingly varied, thereby modifying the effective force exerted on the bellows by the then existing compressor discharge pressure. The action of the bellows 225 thus becomes a function of changes in both pressure and temperature. Also, the shaft 223 may be rotated by the motor 160' in either direction, depending upon whether there is an increase or decrease in temperature in the tailpipe above or below some predetermined value, heretofore described. If there is an increase in temperature, the motor 160' will produce rotation of shaft 223 in a direction which will move the needle 221 outwardly and increase the area of the orifice 218; a drop in temperature having the opposite or reverse effect.

While the temperature sensing device 241 is shown as being subjected to compressor discharge temperature, it could also be subjected to compressor inlet temperature, since compressor discharge temperature at a given engine speed is a function of compressor inlet temperature.

In Figure 4, the potentiometer which corresponds to 192 of Figure 3 is indicated at 242; it has a follow-up mechanical connection with the motor 160' by means of gears 243 and 244, and suitable electrical connections with the switch contact 190 and the bridge circuit at 245.

Operation—Figure 4

The spring rate of the spring 207 is preferably substantially constant, so that the force exerted by said spring may be considered as remaining constant and the respective pressures in chambers 205 and 206 will tend to bear a constant relative value. Thus, the valve 200 will open or close to maintain the pressure in chamber 205, and hence in 203 equivalent to that in 206, plus the force exerted by spring 207. Hence, a substantially constant differential will be maintained across the diaphragm 204, varying only momentarily as the pressure in either of said chambers is varied. The chambers 205 and 212 are connected by two passages in parallel, one comprising the chamber or elongated passage 203 and feed restrictions 211, and the other the fixed bleed 216, chamber 206, passage 217, variable orifice 218, chamber 219 and passage 220. With this arrangement, the drop in pressure from chamber 205 to chamber 212 across the throttle valve ports or feed restrictions 211 will always equal the sum of the drop in pressure from chamber 206 across the fixed bleed orifice 216, the passage 217, variable orifice 218, and passage 220. The substantially constant drop across the fixed orifice 216 as determined by the spring 207 creates a constant rate of fuel flow through orifice 216 which must also pass through 218. Since the rate of flow across the fixed orifice 216 is constant, the drop in pressure across 218 will vary substantially inversely as the square

of the effective area of the latter orifice as determined primarily by the action of the P_e bellows 225 (compressor discharge pressure modified as a function of temperature) and corrected in response to variations in tailpipe temperature above or below a predetermined value through the motor 160' and its coating control circuit of Figure 3. The regulator valve 200 functions to establish an absolute pressure in chamber 205 sufficiently greater than the pressure in chamber 212 to force fuel 5 through the variable area of orifice 218 at a rate determined by the fixed orifice 216 and the constant head thereacross. The metering head across the throttle valve 209 (or feed restrictions 211) is therefore equal to the sum of the constant head across orifice 216 plus the 10 variable head across variable orifice 218. Assuming the afterburning system is turned on and the engine is operating at a speed which will result in the closing of switch 62 of Figure 1, then the tail gate valves 23 and 24 will open and since they are operatively connected to the 15 throttle valve 209, this will result in an increase in the area of the feed restrictions 211, producing an increase in flow of afterburning fuel to the afterburning nozzles. As the P_e pressure increases, the bellows 225 will be compressed in proportion to such increase as modified 20 by compressor discharge temperature and move the needle 221 in a direction to restrict orifice 218, thereby increasing the metering head across the throttle valve 209 and correspondingly increasing the flow of afterburning fuel; a decrease in P_e pressure producing a reverse effect. 25 Should the temperature in the tailpipe vary above or below a predetermined value as determined by the setting of the bridge circuit 172 of Figure 2 in a manner heretofore described, the area of the orifice 218 will be correspondingly varied. If the temperature rises above such 30 value, the area of the orifice 218 will be increased and reduce the metering head; and if the temperature drops below such value, the area of said orifice will be decreased. This tends to maintain the tailpipe temperature constant under full afterburning operation conditions. 35 40 Although only one complete afterburning system plus a modification in the fuel feed control has been illustrated and described, various changes in the form and relative arrangements of the parts may be made to suit requirements.

45 We claim:

1. For use with a gas turbine engine having a primary burner system, a turbine driven compressor for supplying air under pressure to the burner system and a tailpipe downstream of the turbine terminating in a reaction jet, a thrust augmentation or afterburning system comprising means for conducting afterburning fuel under pressure to the interior of the tailpipe between the turbine and reaction jet, means for regulating the flow of fuel as a function of a pressure generated by the compressor, and means operable as a function of tailpipe temperature for modifying the regulated flow of fuel.
2. For use with a gas turbine engine having a primary burner system, a turbine driven compressor for supplying air under pressure to the burner system and a tailpipe downstream of the turbine terminating in a reaction jet, a thrust augmentation or afterburning system comprising means for conducting afterburning fuel under pressure to the interior of the tailpipe between the turbine and reaction jet, means for metering the afterburning fuel as a function of compressor discharge pressure and a temperature varying as a function of compressor inlet temperature, and means for modifying the metering action as a function of an engine operating temperature.
3. In a gas turbine engine having a primary burner system, a turbine driven compressor for supplying air under pressure to the burner system and a tailpipe downstream of the turbine terminating in a reaction jet; means for varying the effective area of said jet, means for actuating said jet area varying means, means for conducting afterburning fuel under pressure to the interior of

the tailpipe between the turbine and reaction jet, means for metering the fuel as a function of a pressure generated by the compressor, means for modifying the quantity of metered fuel as a function of an engine operating temperature, and means for also modifying the quantity of metered fuel in relation to the area of the jet, whereby the fuel metered to said tailpipe varies in accordance with the afterburning fuel requirements of said engine.

4. In a gas turbine engine having a primary burner system, a turbine driven compressor for supplying air under pressure to the burner system and a tailpipe downstream of the turbine terminating in a reaction jet; an afterburner system comprising means for varying the effective area of said jet, means for actuating said jet area varying means, means for conducting afterburning fuel under pressure to the interior of the tailpipe between the turbine and reaction jet, means for metering the fuel in response to changes in a pressure generated by the compressor, means for modifying the metering action in relation to changes in reaction jet area, and means for maintaining an engine operating temperature at a predetermined substantially constant value, whereby the fuel metered to said tailpipe varies in accordance with the afterburning fuel requirements of said engine.

5. The combination as claimed in claim 4 wherein said last-named means comprises a flow regulating valve adapted to modify the metering action and which is automatically positioned by means responsive to variations from a predetermined afterturbine or tailpipe temperature.

6. The combination as claimed in claim 3 wherein means are provided for modifying the compressor generated pressure as a function of a temperature generated by the compressor.

7. In a thrust augmentation system for a turbojet engine having a compressor, a tailpipe chamber, a reaction jet and means for varying the effective area of the jet; means for regulating the flow of fuel to said tailpipe chamber including a fuel conduit having a feed restriction therein, a throttle valve for varying the area of said restriction, a regulator valve for varying the metering head across said restriction, means responsive to changes in a pressure generated by the compressor for controlling one of said valves, means responsive to changes in the area of the reaction jet for controlling the other of said valves, and means for modifying the action of one of said valves as a function of after-turbine or tailpipe temperature, whereby the area of said restriction and the metering head thereacross are controlled to vary the fuel flow to said tailpipe chamber in accordance with the thrust augmentation fuel requirements of said engine.

8. In a thrust augmentation system for a turbojet engine having a compressor, a tailpipe chamber, a reaction jet and means for varying the effective area of the jet; a fuel conduit having a metering restriction therein, a throttle valve for varying the effective area of said restriction, a regulating valve for varying the metering head across said restriction, means responsive to changes in compressor discharge pressure operatively connected to said throttle valve, means responsive to changes in the area of said jet operatively connected to said regulating valve, and means for modifying the action of one of said valves as a function of after-turbine or tailpipe temperature, whereby the fuel flow through said conduit is controlled in accordance with optimum thrust augmentation fuel requirements of said engine.

9. In a thrust augmentation system for a turbojet engine having a compressor, a tailpipe chamber, a reaction jet and valve means for varying the effective area of the jet; a fuel conduit having a metering restriction therein, a throttle valve for varying the effective area of the restriction; a regulating valve for controlling the metering head across said restriction, said valve means being operatively connected to said throttle valve, pressure responsive means connected to said regulating valve, and means

for repositioning said pressure responsive means as a function of a pressure generated by the compressor, whereby fuel may be metered to said tailpipe chamber in accordance with the thrust augmentation requirements of said engine.

10. A system as claimed in claim 9 wherein means responsive to changes in after-turbine or tailpipe temperature above or below a predetermined value is arranged to also reposition said pressure responsive means.

11. A system as claimed in claim 9 wherein said pressure responsive means is operatively connected to a variable by-pass bleed or orifice having a needle for varying the effective area thereof, said needle being controlled by means responsive to changes in compressor discharge pressure and also by means responsive to changes in after-turbine or tailpipe temperature.

12. In a thrust augmentation system for a turbojet engine having a tailpipe chamber and a reaction jet; means for metering fuel to said tailpipe chamber, and means operable to automatically render said metering means operative only after the rotational speed of the engine has attained a predetermined value.

13. In a thrust augmentation system for a turbojet engine having a tailpipe chamber, a reaction jet and valve means for varying the effective area of said jet; means for metering fuel to said tailpipe chamber and means responsive to changes in the rotational speed of the engine for initiating the operation of said metering means and said valve means.

14. In a thrust augmentation system for a turbojet engine having a tailpipe chamber, a reaction jet and means for varying the effective area of the jet; means for metering fuel to said tailpipe chamber including a fuel manifold and a series of discharge nozzles receiving fuel under pressure from said manifold, and a speed sensitive device responsive to changes in the rotational speed of the engine for initiating flow of fuel to said manifold and discharge nozzles and also for producing operation of said area varying means.

15. In an afterburning system for a turbojet engine having a tailpipe chamber, a fuel metering device, a temperature sensing device for modifying the action of the fuel metering device to maintain a predetermined engine operating temperature by controlling the rate of fuel feed while the afterburning system is in operation; and means for automatically maintaining a predetermined fixed relationship between said devices having as its modulus a given tailpipe chamber temperature when said system is in a nonoperating or idle condition.

16. In a system for burning fuel in the tailpipe of a turbojet engine after the turbine, a fuel metering device having a valve for controlling the rate of fuel flow, a temperature responsive device having an element for sensing the temperature in the tailpipe, means connecting said temperature responsive device to said valve to regulate fuel flow in response to changes in tailpipe temperature above or below a predetermined value, and means for automatically maintaining said temperature responsive device and said valve in a predetermined relationship having as its modulus a given tailpipe temperature when the afterburning system is in non-operating condition.

17. In a system for burning fuel in the tailpipe of a turbojet engine, fuel metering means having a valve for controlling the rate of fuel flow, and means for positioning said valve as a function of tailpipe temperature; said latter means including an electrical valve actuating device, a thermal responsive element for sensing tailpipe temperature, means for transmitting signals from said element to said valve actuating device including an electric circuit having an adjustable bridge therein which is calibrated to balance when the tailpipe temperature is at a predetermined value and to become unbalanced when the temperature is above or below such value, a member movable to vary the flow of current through the bridge having a follow-up connection with the motor, said latter member

when in a neutral position balancing the bridge, and means for electrically disconnecting the bridge from said element when the system is idle and connecting it to said latter member to automatically "spot" the valve at a position corresponding to that which it assumes when the thermal responsive element and bridge are electrically connected and in balance.

18. In a thrust augmentation system for a turbojet engine having a compressor, a burner and a tailpipe chamber; means for regulating the flow of fuel to said tailpipe chamber including a fuel conduit having a feed restriction therein, a valve for regulating the flow of fuel through said restriction, a pressure-responsive device operatively connected to said valve, means for subjecting said device to a pressure varying as a function of compressor discharge pressure, and means operable as a function of a temperature which varies with variations in compressor inlet temperature for modifying the pressure to which said device is subjected, whereby the flow of fuel through said restriction to said tailpipe chamber varies as required.

19. A system as claimed in claim 18, wherein air pressure is communicated to said device through a conduit having a variable orifice therein, and the area of said orifice is regulated by a valve which is operatively connected to an element responsive to changes in compressor discharge temperature.

20. In a thrust augmentation system for a turbojet engine having a compressor, a tailpipe chamber, a reaction jet and means for varying the effective area of the jet; means for regulating the flow of fuel to said tailpipe chamber including a fuel conduit having a feed restriction therein, a throttle valve for varying the area of said restriction, a regulator valve for varying the metering head across said restriction, means responsive to changes in temperature varying with changes in compressor inlet temperature for actuating one of said valves, means responsive to changes in the area of the reaction jet for actuating the other of said valves, and means for modifying the action of one of said valves as a function of after-turbine or tailpipe temperature, whereby said regulating means functions to meter fuel to said tailpipe chamber in accordance with the thrust augmentation fuel requirements of said engine.

21. In a thrust augmentation system for a turbo-jet engine having a tailpipe chamber and a reaction jet; means for conducting afterburner starting fuel to said tailpipe chamber, means for igniting the starting fuel flow, and means operable to permit the flow of starting fuel to the tailpipe chamber and to energize said ignition means only after the rotational speed of the engine has attained a predetermined value.

22. In a thrust augmentation system for a turbo-jet engine having a tailpipe chamber and a reaction jet; a pump for pressurizing fuel to said tailpipe chamber, and means operable to automatically render said pump operative only after the rotational speed of the engine has attained a predetermined value.

23. In a thrust augmentation system for a turbo-jet engine having a tailpipe chamber and a reaction jet; a temperature sensing device adapted to respond to variations in the temperature in said tailpipe from a predetermined value, and means operable to automatically render said sensing device responsive to the temperature variations only after the rotational speed of the engine has attained a predetermined value.

24. In a thrust augmentation system for a turbo-jet engine having a tailpipe chamber and a reaction jet; a temperature sensing device adapted to respond to variations in the temperature in said tailpipe from a predetermined value for producing a signal which varies in magnitude as a function of the degree of variation from said predetermined temperature value, and means operable to automatically render said sensing device responsive to

said temperature variations only after the rotational speed of the engine has attained a predetermined value.

25. In a thrust augmentation system for a turbo-jet engine having a tailpipe chamber and a reaction jet; means for metering fuel to said tailpipe chamber, a temperature sensing device for modifying the action of said metering means to maintain a predetermined engine operating temperature by controlling the rate of fuel feed to said chamber while the thrust augmentation system is in operation, and means operable to automatically render said temperature sensing device operative to maintain said predetermined temperature only after the rotational speed of the engine has attained a predetermined value.

15 26. In a thrust augmentation system for a turbo-jet engine having a tailpipe chamber and a reaction jet; means for metering fuel to said tailpipe chamber including a main after burner fuel conduit means, and means operable to permit a flow of fuel through said conduit means to said tailpipe chamber only after the rotational speed of the engine has attained a predetermined value and only after tailpipe chamber temperature has attained a predetermined value.

25 27. In a thrust augmentation system for a turbo-jet engine having a tailpipe chamber and a reaction jet; valve means for varying the effective area of said jet, means for actuating said valve means, means responsive to a change in engine speed, and means responsive to a change in tailpipe chamber temperature, said speed and temperature responsive means being operatively connected to said actuating means in such a manner that said valve means is actuatable from a relatively closed to a relatively open condition only after engine speed and tailpipe chamber temperature have attained predetermined values.

35 28. In a thrust augmentation system for a turbo-jet engine having a tailpipe chamber, a reaction jet and valve means for varying the effective area of the jet; means for actuating said valve means, and means operable to automatically render said actuating means operative to open said valve means only after the rotational speed of the engine has attained a predetermined value.

35 29. In an afterburner system for a turbo-jet engine having a tailpipe chamber, a reaction jet and means for varying the effective area of said jet; means for actuating said valve means, means for metering fuel to said tailpipe chamber operatively connected to and coordinated with said actuating means, and means operable to automatically render said metering means and said actuating means operative for afterburner operation only after the rotational speed of the engine has attained a predetermined value.

50 30. A system as claimed in claim 29 wherein means responsive to tailpipe chamber temperature is also adapted to render said metering means and said actuating means operative for afterburner operation.

55 31. In a thrust augmenting system for a gas turbine engine having a compressor, a tailpipe chamber, and a reaction jet; a conduit for conducting fuel to said chamber, and fuel control means for controlling the quantity of fuel flowing through said conduit including a fuel metering restriction in said conduit, a metering valve controlling the area of said restriction, an independent fuel pressure differential responsive regulator valve controlling the metering head across said restriction, and means responsive to a pressure generated by the compressor and operatively connected to said metering valve for varying the fuel flow through said restriction as a function of said generated pressure, whereby the fuel flow through said conduit is regulated by the coordinated action of said metering and regulator valves.

60 70 32. In a thrust augmenting system for a gas turbine engine having a compressor, a tailpipe chamber, a reaction jet and means for varying the effective area of the jet; a conduit for conducting fuel to the tailpipe chamber, valve means for controlling the fuel flow through said conduit, first means responsive to a pressure generated

by the compressor operatively connected to said valve means for controlling the flow of fuel therethrough as a function of said generated pressure, second means responsive to an engine operating temperature operatively connected to said valve means for modifying the flow of fuel therethrough as a function of said temperature, and third means for modifying the pressure to which said pressure responsive means responds.

33. In a fuel control system for a gas turbine engine having a combustion chamber and a compressor, a fuel nozzle for discharging fuel under pressure into said combustion chamber, a conduit for conducting fuel to said nozzle, and fuel flow control means in said conduit including a metering restriction, a metering valve controlling the area of said restriction, an independent fuel pressure differential responsive regulator valve controlling the metering head across said restriction, and means responsive to a pressure generated by the compressor and operatively connected to one of said valves for varying the flow of fuel through said restriction as a function of said generated pressure.

34. In a thrust augmentation system for a turbojet engine having a tailpipe chamber, a reaction jet and a compressor; means for metering fuel to said tailpipe chamber, means operable to automatically render said metering means operative only after the rotational speed of the engine has attained a predetermined value, with said metering means including means responsive to the discharge pressure of said compressor.

35. In a thrust augmentation system for a turbojet engine including a tailpipe chamber, a compressor, a reaction jet, and valve means for varying the effective area of said jet; means for metering fuel to said tailpipe chamber and means responsive to changes in the rotational speed of the engine for initiating the operation of said metering means and said valve means, with said metering means including a device responsive to a pressure generated by said compressor.
